Des. 237,477
Patented Nov. 4, 1975

237,477

AIR DEFLECTOR FOR PICKUP TRUCKS OR THE LIKE

Giles P. Lay, 11 E. Norma St.,
Sulphur, Okla. 73086

Filed May 22, 1974, Ser. No. 472,237

Term of patent 14 years

Int. Cl. D12—16

U.S. Cl. D12—98

FIG. 1

FIG. 2

FIG. 1 is a side elevational view of an air deflector for pickup trucks or the like showing my new design, the opposite side being a mirror image thereof.

FIG. 2 is a top plan view thereof.

FIG. 3 is a front elevational view thereof.

FIG. 4 is a rear elevational view thereof.

FIG. 5 is a bottom plan view thereof.

I claim:

The ornamental design for an air deflector for pickup trucks or the like, substantially as shown.
